DESIGN FOR A SHOE

Christy Reggie, Waynesville, N. C.

Application October 22, 1946, Serial No. 134,166

Term of patent 7 years

(Cl. D7—7)

To all whom it may concern:

Be it known that I, Christy Reggie, a citizen of the United States of America, residing in Waynesville, county of Haywood, and State of North Carolina, have invented a new, original, and ornamental Design for a Shoe, of which the following is a specification, reference being had to the accompanying drawing, forming part thereof.

Fig. 1 is a perspective view of a shoe showing my new design.

Fig. 2 is a perspective view of the opposite side of the shoe shown in Fig. 1.

Fig. 3 is a rear perspective view of the heel portion of the shoe.

The dominant feature of my design resides in the portion shown in solid lines.

I claim:

The ornamental design for a shoe, substantially as shown and described.

CHRISTY REGGIE.
